(57) **CLAIM**

The ornamental design for a mask filter, as shown and described.

DESCRIPTION

FIG. 1 is a top perspective view of a mask filter in an open configuration;

FIG. 2 is a bottom perspective view of the mask filter of FIG. 1;

FIG. 3 is a top view of the mask filter of FIG. 1;

FIG. 4 is a right side view of the mask filter of FIG. 1;

FIG. 5 is a bottom view of the mask filter of FIG. 1;

FIG. 6 is a left side view of the mask filter of FIG. 1;

FIG. 7 is a front view of the mask filter of FIG. 1;

FIG. 8 is a back view of the mask filter of FIG. 1;

FIG. 9 is a top perspective view of the mask filter in a closed configuration;

FIG. 10 is a bottom perspective view of the mask filter of FIG. 9;

FIG. 11 is a top view of the mask filter of FIG. 9;

FIG. 12 is a right side view of the mask filter of FIG. 9;

FIG. 13 is a bottom view of the mask filter of FIG. 9;

FIG. 14 is a left side view of the mask filter of FIG. 9;

FIG. 15 is a front view of the mask filter of FIG. 9; and,

FIG. 16 is a back view of the mask filter of FIG. 9.

The broken lines in the drawings depict portions of the mask filter that form no part of the claimed design.

1 Claim, 6 Drawing Sheets
